UNITED STATES PATENT OFFICE

140,388

DESIGN FOR A POWDER BOX OR SIMILAR ARTICLE

John D. Buckingham, Chicago, Ill., assignor to
Lucien Le Long, Inc., Chicago, Ill., a corporation
of Illinois

Application November 10, 1944, Serial No. 116,270

Term of patent 14 years

(Cl. D58—11)

To all whom it may concern:

Be it known that I, John D. Buckingham, a citizen of the United States and a resident of the city of Chicago, in the county of Cook and State of Illinois, have invented a new, original, and ornamental Design for a Powder Box or Similar Article, of which the following is a specification, reference being had to the accompanying drawing, forming a part thereof.

On the drawing:

Figure 1 is a top plan view of the powder box or similar article, showing my new design;

Figure 2 is a side elevational view;

Figure 3 is a front elevational view; and

Figure 4 is a rear elevational view thereof.

I claim:

The ornamental design for a powder box or similar article, as shown.

JOHN D. BUCKINGHAM.
